UNITED STATES PATENT OFFICE.

ARTHUR W. COFFIN, OF OAKLAND, CALIFORNIA, ASSIGNOR TO THE COFFIN COMBINATION PUNCH AND TICKET COMPANY, OF SAME PLACE.

CONDUCTOR'S RECORDING-PUNCH.

SPECIFICATION forming part of Letters Patent No. 434,142, dated August 12, 1890.

Application filed November 22, 1889. Serial No. 331,239. (No model.)

To all whom it may concern:

Be it known that I, ARTHUR W. COFFIN, a citizen of the United States, residing at Oakland, Alameda county, State of California, 5 have invented an Improvement in Conductors' Punches; and I hereby declare the following to be a full, clear, and exact description of the same.

My invention relates to the class of conductors' punches; and it consists in the novel constructions, combinations, and arrangement of the several parts hereinafter fully described, and specifically pointed out in the claims.

15 The object of my invention is to provide a simple and efficient conductor's punch capable of carrying within itself a necessary number of tickets and their duplicates, both of which in their simultaneous passage through 20 the machine are similarly marked or punched, one being given to the passenger and the other retained in the machine.

Referring to the accompanying drawings for a more complete explanation of my invention, Figure 1 is a perspective view of my punch. Fig. 2 is a vertical longitudinal section. Fig. 3 is an enlarged section of the discharge end. Fig. 4 is a view of the under side of cap e. Fig. 5 is a plan of the ticket.

30 A is the frame or case of the machine, having a bail or loop a, by which it may be readily strapped to the person. At one end of the case is formed a chamber B, which is closed by a hinged cap-plate b. Across the upper 35 part of this chamber is mounted a shaft C and across the lower portion of the chamber is mounted a shaft D, said shafts having at one end intermeshing gears c and d. At the other end of the case is formed a chamber E, 40 which is closed by a hinged cap e, through the top of which is made a transverse opening e'. In the top of this cap, at a point just forward of the opening, is located the sliding knife F, having a thumb or finger flange f, by which 45 it is operated. This knife has downwardly-projecting guide-studs f', extending through elongated guide-slots in the cap, and are operated upon by a spring f'', so that the knife is held normally back away from the transverse

opening, but may be pushed forwardly across 50 said opening when desired. Under the cap and on each side of the transverse opening e' are flanged plates e'', serving as guide-walls for said opening.

Within the chamber E is mounted transversely the winding-shaft G, having on its outer end a thumb-wheel g for operating it. On the shaft within the casing is a ratchet g', with which engages a spring-controlled pawl g'', which will permit the shaft to be 60 turned forwardly but not backwardly. Through the body of the casing is made longitudinally a ticket-passage, (represented by H.)

I are punches or markers consisting of suitable presser-heads located above the casing and having shanks which pass freely down through the top wall of the casing, their lower ends carrying a number of needle-points i, which are arranged to represent the different 70 figures. Springs J encircle the shanks of the punches to hold them normally raised and to return them after being pressed down. The needle-points of the punches play through the top wall of the ticket-passage and traverse it, 75 so that they pass through the tickets within said passage. The arrangement of these punches is in series, as follows: One longitudinal line may represent dollars and be marked from 1 upwardly, as desired. The next line 80 represents dimes, and the next line represents cents, and the head of each punch is appropriately marked.

In the forward end of the case is located a pair of feed-rollers K, the lower one of which 85 preferably consists of a rubber friction-roller and the upper one of a metal roller provided with a roughened surface for better engagement with the tickets. These rollers have intermeshing gears k at their ends for causing 90 their action in unison. Immediately before these rollers is a directing-plate L. The cap b of the rear chamber may be held to place temporarily by a suitable latch, as shown at b', and the cap e of the forward chamber may 95 be likewise held closed by a catch e''; but in order to lock these chambers, so as to prevent their being tampered with, except by the

proper authority, I have a locking-bolt M. Upon one side of the cap b is a perforated lug or ear b², recessed or made hollow, as shown. This ear fits against a perforated lug a' on 5 the side of the casing, and upon the forward end of the case, on the same side, is located a guide-sleeve a², which is in line with a nut e⁴ on the cap of the forward chamber. The bolt M passes through these several parts, so 10 as to bind and lock them all together. Its outer end is threaded, and it screws into the nut of the forward cap, while its head is seated in the recess of the lug or ear b², and said head is then covered up completely with sealing-wax seated in the recess of the lug or ear, 15 so that the locking-bolt is thereby sealed and cannot be tampered with without detection.

Upon the upper shaft C, in the rear chamber B, is wound the roll N of original tickets, 20 said tickets being formed in one continuous strip of suitable material, printed at intervals with the matter suitable for tickets—as, for example, a number, three columns represented and marked as dollars, dimes, and cents, and 25 other matter which may be found necessary. Upon the lower shaft D within said chamber is mounted the duplicate roll O of tickets, which may be a plain strip, or, if desired, exactly corresponding to the roll N on the shaft C. The 30 ends of these two rolls are carried together into and through the ticket-passage H the one upon the other, and they are brought forwardly through between the feed-rollers K at the forward end of the case. Thence the original 35 ticket-strip is directed upwardly through the aperture e' in the top of the cap e, while the end of the duplicate roller is directed and secured to the shaft G within the chamber E.

The operation of the punch is as follows: 40 It is fully loaded, locked, and ready for use when handed to the conductor. When he desires to give a ticket, he first punches the proper amount of money received by manipulating the proper punches or markers of the 45 device, so that their needle-points passing across the ticket-chamber H penetrate both the original and duplicate tickets. As soon as this is done he turns the thumb-wheel g of the shaft G forwardly, so as to wind up the 50 duplicate ticket, and this, by reason of its contact with the original ticket, and the two passing through between the pair of feed-rollers K, causes the original ticket to move forwardly also and gradually emerge from 55 the opening e' in the cap e. As soon as it is fully emerged the conductor presses forward the sliding-knife plate F across the opening, and thereby cuts off the ticket. The duplicate ticket, however, is not cut off at all, but 60 is simply wound upon the shaft G. Now, for the next ticket, the conductor punches it as

before, and then once more turns the shaft G, so that the duplicate strip is continued to be wound upon the shaft, while the original ticket-strip is again projected and cut off by 65 the sliding-knife plate. Thus when the conductor delivers up his punch to the auditor's office, it will be found from the roll of duplicate tickets on the shaft G the exact amount and character of the tickets which he has disposed of to the passengers. 70

It is not essential that the duplicate roll shall have any printed matter upon it at all. It may be a plain strip of any suitable material; but for convenience I have referred to it 75 as a duplicate roll of tickets.

Having thus described my invention, what I claim as new, and desire to secure by Letters Patent, is—

1. A conductor's punch consisting of a casing 80 having at one end a chamber, a hinged cap-plate for closing said chamber, a shaft C in the upper part of said chamber and a second shaft D in the lower part thereof, and intermeshing gears at one end of the said 85 shafts, a second chamber at the opposite end of the casing closed by a hinged cap e, provided with a transverse opening e', complementary punching mechanism and strip-holding rolls within the casing between the 90 two end chambers, a winding-shaft within the second chamber having a thumb-wheel for winding the duplicate strip on said shaft, a sliding knife or cutter operating across the transverse opening e' to sever the ticket, and 95 a pawl and a ratchet mechanism for the winding-shaft, substantially as herein described.

2. An improved conductor's punch consisting of a casing having a chamber at each end, 100 said chambers each having a hinged cap-plate for closing them, the geared shafts C and D within one of said chambers and containing the original and duplicate strip, respectively, a single winding-shaft in the opposite chamber for receiving the duplicate 105 sheet, a thumb-wheel on said shaft for operating it, complementary punching mechanism, two holding-rolls in advance of the winding-shafts for holding the strips, a sliding cutter mounted in the cap e, which has 110 an opening through which the original strip passes, and a mechanism, as described, for locking the hinged plates, whereby the punch is sealed, substantially as and for the purpose described. 115

In witness whereof I have hereunto set my hand.

ARTHUR W. COFFIN.
